UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

1,414,738.

Specification of Letters Patent. Patented May 2, 1922.

Application filed June 19, 1919. Serial No. 305,255.

To all whom it may concern:

Be it known that I, WILLIAM F. HELMOND, a citizen of the United States, residing in Hartford, in the county of Hartford 5 and State of Connecticut, have invented certain new and useful Improvements in Type-writing Machines, of which the following is a specification.

This invention relates to back-spacing 10 mechanism for typewriting machines of the type disclosed in my Patent No. 930,962 granted August 10, 1909.

According to the present improvements, upon depression of a back-spacing key 15 against the action of a spring associated therewith, a link connected to the back-spacing dog or pawl at one side of its pivot will be actuated to permit the pawl to be moved into engagement with the usual rack, by 20 means of a spring acting on the pawl carrier, and upon said carrier reaching its forward limiting pawl-engaging position, the pawl will be swung about its pivot, by the back-spacing key acting through the connecting link, to back-space the rack and consequently the carriage. Upon release of said back-spacing key the spring associated therewith will cause the link to move in a reverse direction and disengage the pawl 25 from the rack, and thereafter move said pawl to normal position on its carrier and restore the latter to normal position against the action of the spring associated therewith.

30 Hitherto, the shaft carrying the back-spacing key-lever has been supported beneath the usual key-lever bridge at the rear of the machine, and the forward end of the actuating arm for the link connected to the back-spacing pawl has been positioned directly beneath the rack; consequently the leverage exerted by the link to turn the back-spacing pawl carrier about its pivot has been very slight.

35 In the present arrangement the shaft on which the back-spacing key lever is fixed is mounted at the front of the key-lever bridge, and the shaft is provided with an arm whose forward extremity extends below the usual 40 bell-crank bridge. The link connected to the back-spacing pawl is bent so as to extend under the bell-crank bridge and is pivotally connected to the forward end of the arm extending thereunder. This bent link 45 obviously has the same effect as would be

obtained by a straight link connecting the pivot point on the forwardly extending arm and the pivot point for the link on the back-spacing pawl, thus giving much greater leverage and enabling the use of a lighter 60 spring associated with the back-spacing key-lever than would otherwise be required.

It will be seen that by the present improved structure, it is made possible to omit the usual pawl latch and the usual spring 65 connecting the pawl and the link, such as shown in said patent, and that greater simplicity of structure and ease of action are thereby obtained.

Other features and advantages will hereinafter appear.

In the accompanying drawings,

Figure 1 is a diagrammatic side elevation, partly in section, illustrating my invention as applied to an Underwood typewriting 75 machine.

Figure 2 is a fragmentary front view, showing the back-spacing pawl in normal position.

Figure 3 is a view similar to Figure 2, 80 showing the parts in the position assumed at the end of a back-spacing movement.

Figure 4 is a skeleton perspective view of the parts constituting the invention.

Figure 5 is a side view from the right of 85 the parts positioned as shown in Figure 3.

In the machine herein disclosed, depression of character keys 1 will act through key-levers 2 and bell-cranks 3, to swing type-bars 4 upwardly and rearwardly to cause engagement of types 5 with the platen 6, rotatably supported in the platen frame 7 mounted in a carriage 8, which is carried on front and rear rails 9 and 10, respectively, and is urged in one direction by means of the usual strap 90 11 and spring drum 12.

The movement of the carriage, under urging of spring drum 12, is controlled by means of a rack 13 connected with the carriage 8 in the usual manner and a pinion 14 having 100 a one-way connection with an escapement wheel 15 by means of pawls 16 controlled by springs (not shown). The movement of the escapement wheel 15 is controlled by the usual mechanism, not shown.

Key-levers 2 are pivoted on the usual key-lever bridge 17 at the rear of the machine by means of a rod 18, and springs 19 positioned between said bridge 17 and key-levers 2 urge said levers to their normal positions. 110

The machine is also provided with a second bridge 20, in which the bell-crank 3 are pivoted by means of a rod 21.

When a back-spacing action is desired, a 5 back-space key 22 is depressed, and such movement is transmitted by means of a lever 23 to a shaft 24 mounted in a bracket 25 on the front of bridge 17. Slightly to the right of the center of the machine, an arm 26 is 10 secured to shaft 24, and a head 27 of said arm 26 lies under said bell-crank bridge 20. A restoring spring 28 connected to a pin 29, passing through said head 27 and to bracket 25, tends to hold the back-space key in raised 15 position.

Upon depression of key 22, and consequent depression of arm 26, movement is transmitted to a bent link 30 secured to head 27 by means of pin 29 and pivoted loosely at 31 20 to a laterally extending lug or operating arm 32 forming part of a back-space pawl 33. A support or carrier 34 for the back-space pawl 33 is pivotally mounted at 35 for forward and back movement toward and 25 from rack 13 transversely thereof, and is provided with a hook 36 which engages a stud or pin 37 mounted on a fixed part of the frame for the purpose of limiting the movement of said support. The upper end of said 30 support is provided with the usual hook to prevent upward displacement of said rack 13 during the back-spacing operation. The back-space pawl 33 is mounted for letter-spacing movement on support 34 by means 35 of a pivot 38, whose axis is at right angles to that at the carrier pivot 35, so as to form therewith a universal joint mounting for the pawl 33. The pivot 31, connecting the upper end of the link 30 to the pawl-arm 32, 40 has a sufficiently loose connection with this pawl-arm to permit the pawl 33 to swing forward and backward with the pawl-carrier 34 as the latter swings on its pivot 35.

The retractive movement of pawl 33 about 45 its pivot 38 on the carrier 34 is limited by a lug 39 on the carrier, and said pawl is normally held in this position by means of spring 28, which normally exerts an upward pressure on link 30 sufficient to hold pawl or 50 dog 33 in retracted position in engagement with lug 39, and also to hold carrier 34 in its rearward pawl-disengaging position against the action of a spring 40 rigidly secured at its lower end to carrier 34 by means of a 55 pin 41 and engaging stud 37 at its upper end.

It will be seen that downward movement of link 30 has, as its first effect, to relieve the spring 40 from the overpowering opposing influence of the stronger pawl-restoring 60 spring 28, and thereby will enable spring 40 to swing carrier 34 to a pawl-engaging position limited either by engagement of the same with rack 13, or by engagement of hook 36 with stud 37, and that as soon as pawl 33 65 is brought into engagement with rack 13

further movement of link 30 will cause dog 33 to be swung to the right to give a back-spacing movement to rack 13 and consequently to carriage 8.

It will be understood that the springs 28 and 40 exert opposing pressures at the pivot 31, the spring 28 urging the link 30 and pivot-pin 31 in an upward and rearward direction, while the spring 40, acting through the pawl-carrier and the pawl 33 carried thereby, urges the pawl-arm 32 in the opposite direction, that is, downward and forward. When the link 30 and pivot-pin 31 carried thereby are moved downward and forward as a result of depressing the space-key 22, the pawl-carrier 34 and the pawl 33 carried thereby are moved forward by the spring 40, with the result that the pawl-arm 32 will be moved downward and forward as fast as it is permitted to move by the re-treating or downwardly and forwardly moving pivot-pin 31 on the link 30.

Thus, it will be seen that the pawl 33 is moved to its engaging position with the rack 13 by the push of the spring 40 on the pawl-carrier 34, and that this pawl is not moved to this rack-engaging position by the link 30. In view of the fact that the link 30 does not exert any pulling effect upon the pawl-arm 32, it will be evident that the pawl 33 cannot be swung on its pivot 38 until after the forward movement of the pawl-carrier 34 by the spring 40 has been stopped by the stud 37 or by the rack 13, as shown in Figure 5. During this pawl-engaging 100 movement, the spring 40 will hold the pawl 33 tightly against its back-stop lug 39, by reason of the fact that the spring 40 has a tendency to move the pawl-carrier 34 faster than it is permitted to move by the key-controlled combined downward and forward movement of the link 30, so that thereby upward and rearward pawl-restraining pressure is maintained by the pivot 31 on the pawl-arm 32 throughout the pawl-engaging 110 movement of the carrier 34 and pawl 33.

In the construction heretofore employed, and disclosed in my above-mentioned patent, it was found necessary to provide a spring-pressed latch to prevent the pawl from 115 swinging on its pivot on the pawl-carrier before this pawl had moved into engagement with the rack, and, furthermore, to provide a spring to resist the tendency of the operating link to swing the pawl or dog about 120 its pivot, such spring co-operating with the latch. In the present invention, the provision of the single spring 40 enables the previously-employed latch, the latch spring and the pawl spring all to be dispensed with. 125 It has been found in practice that the present construction operates more easily, freely, smoothly and with more certainty than in the previous device, so that the efficiency of the back-spacing mechanism is increased to 130

a marked degree by means of a simple and inexpensive construction. This previous construction, besides being less reliable and less effective than the device provided by the 5 present invention, resulted in a heavy key-action, whereas in the device of the present invention the key-action has proved much lighter.

The back-spacing movement of rack 13 10 effects rotation of pinion 14 with reference to escapement wheel 15, which is prevented from moving with the pinion by means of a pivoted dog 42 swung into position to prevent backward rotation of the escapement wheel. The connection between the 15 dog 42 and carrier 34 may be effected by any suitable means, such, for example, as that shown in said Patent No. 930,962. As is made clear in said patent, unless provision 20 is made of means such as the dog 42, a back-spacing movement of rack 13 with pinion 14 would cause a corresponding movement of escapement wheel 15 and of the usual loose dog, and upon release of the back-spacing key the escapement wheel, under 25 control of the spring drum, would merely move the loose dog to its original position and no back-spacing would be effected.

Movement of the back-spacing pawl 33 to 30 the right, in the back-spacing operation, is limited by means of a stop 43 at its lower end coming into contact with the pawl-carrier 34, and, due to the manner in which pawl 33 is brought into engagement with rack 13, 35 the limitation of movement of the pawl will also serve to limit the back-spacing movement of the rack.

Upon release of key 22 by the operator 40 at the end of a back-spacing movement, the spring 28 will act to restore key 22 to normal position and will swing the carrier 34 to the rear against the action of the spring 40, to disengage pawl 33 from rack 13, and subsequently the spring 28 will restore said 45 pawl to its normal retracted position on carrier 34.

Hitherto, due to position of bridges 17 and 50 20, it has been thought necessary to use a substantially straight link, extending from the back-space pawl vertically downwardly 55 between the bridges, and to actuate the link by means of an arm on a shaft supported beneath the rear portion of the key-lever-bridge, said shaft also carrying the back-space-key lever. With this construction, the effective action of the link was along a line passing so close to the pivot or fulcrum of the pawl-carrier that the leverage for turning the carrier about the pivot was very 60 slight, and it was, therefore, necessary to provide a strong resistance to the swinging movement of the pawl relative to said carrier, such, for example, as the spring-pressed latch for the pawl and the pawl-retarding 65 spring, disclosed in my previous patent,

hereinbefore referred to, to prevent such movement before the pawl was brought into engagement with the rack. A heavy key action resulted from this arrangement, and in the present case there is provided a 70 greater leverage about pivot 35 in order to avoid the use of a very strong spring 28 to overcome spring 40. This long leverage applied to the pawl-carrier 34 to swing it about the pivot 35 is shown as somewhat greater 75 than the leverage on the pawl 33 to swing it on its pivot 38, and this helps to make sure that the pawl 33 will not be moved on its pivot 38 before it is brought into engagement with the rack 13.

The above-mentioned difficulty has, however, been obviated by supporting shaft 24 at the front of key-lever-bridge 17, with arm 26 extending beneath bridge 20, and by forming link 30 with a bend near its lower 80 end, so that it extends beneath bridge 20 and between the bridges 17 and 20. Obviously said link 30 produces the same effect as would be obtained by a straight link joining pivot pin 29 and pivot 31. The present 85 structure therefore affords a much greater leverage about pivot 35 than was obtained in the structure formerly in use, and makes it possible to use a much weaker spring 28 than would otherwise be required.

It will be obvious that since spring 28 and spring 40 oppose each other, they may be selected so as to obtain a very easy key action, and that considerable simplification of the parts for controlling the back-spacing-pawl 100 and the carrier therefor has been effected, as hereinbefore noted. Thus it will be seen that the link 30 and the spring 40 co-operate with each other and with other parts of the device, not only to give a light key-action, 105 but also to assure that the carrier 34, impelled by the spring 40, will swing the pawl 33 into engagement with the rack 13 before the pawl is moved on the carrier for effecting the back-spacing operation. Because 110 of the fact that the pawl-carrier 34 is pushed to its pawl-engaging position by the spring 40, instead of being pulled over by the link 30, as heretofore, friction of the pawl-carrier on its pivot 35, as well as in all the connections, is lessened, which also, of course, gives an easier key-action.

Variations may be resorted to within the scope of the invention, and portions of the improvements may be used without others.

Having thus described my invention, I claim:

1. In a typewriting machine, the combination with a traveling carriage and an escapement mechanism therefor including a 125 rack connected to the carriage to travel therewith, of a pawl-carrier mounted for movement transversely to the letter-spacing movement of the rack, a back-spacing pawl mounted on the pawl-carrier to have letter- 130

spacing movement thereon, means for limiting the letter-spacing movement of the pawl on the pawl-carrier, a pawl-carrier-engaging spring for continually urging the pawl-carrier towards the rack for moving the pawl carried thereby into engagement with the rack, and manually-controlled operating means for normally holding the pawl-carrier away from the rack with the pawl 5 engaged therefrom against the tension of the pawl-engaging spring, but said operating means being operable to permit the pawl-engaging spring to move the pawl-carrier towards the rack to engage the pawl therewith, and then said operating means by continued movement acting to move the pawl on the pawl-carrier to move the rack to back-space the carriage.

2. In a typewriting machine, the combination with a carriage and an escapement mechanism therefor including a rack connected to the carriage to travel therewith, of back-spacing mechanism comprising a pawl-carrier pivoted for pawl-engaging and 20 disengaging movements transversely to the rack, means to limit the movements of the pawl-carrier, a back-spacing pawl pivoted on the pawl-carrier to have letter-spacing movement thereon, means to limit the letter-spacing movement of the pawl on the pawl-carrier, a pawl-carrier-engaging spring for continually urging the pawl-carrier toward its position for engaging the pawl with the rack, spring-operated mechanism connected 25 with the pawl to hold the pawl at its retracted letter-spacing position and to hold the pawl-carrier at its pawl-disengaging position against the tension of the pawl-engaging spring, and manually-controlled operating means to overcome the spring-operated mechanism to enable the pawl-engaging spring to move the pawl-carrier to engage the pawl with the rack, and then said operating means by continued movement acting 30 to swing the pawl on the pawl-carrier to move the rack for back-spacing the carriage.

3. In a typewriting machine having key-levers, a bridge in which said levers are pivoted at the rear of the machine, a second 35 bridge in advance of said key-lever bridge and overlying said key-levers, the combination with a traveling carriage and a rack connected therewith in position above the space between said bridges, of a back-space 40 pawl, a support for said pawl pivoted below said rack for movement to carry said pawl into and out of engagement therewith, and means to swing said support to bring said pawl in engagement with said rack and actuate 45 said pawl including a pivotally mounted arm extending under said second bridge, and a link pivoted at one end to said pawl at a point to one side of the pawl pivot and at the other end to said arm at a point beneath said second bridge.

4. In a typewriting machine, the combination with a traveling carriage and an escapement mechanism therefor including a rack connected to the carriage to travel therewith, of a back-spacing pawl mounted 70 for movement transversely of the rack into and out of engagement therewith and for letter-spacing movement to move the rack for back-spacing the carriage, a spring for continually urging the pawl in a direction 75 transversely of the rack for engaging it therewith, pawl-restoring means including a spring for holding the pawl at its retracted letter-spacing position and for overcoming the pawl-engaging spring to hold the pawl 80 at its disengaged position clear of the rack, and manually-controlled operating means to overcome the pawl-restoring means to enable the pawl-engaging spring to move the pawl into engagement with the rack, and 85 then said operating means by continued movement acting to impart letter-spacing movement to the pawl to move the rack for back-spacing the carriage.

5. In a typewriting machine, the combination with a traveling carriage and an escapement mechanism therefor, including a rack connected to the carriage to travel therewith, of back-spacing mechanism comprising a back-spacing pawl pivoted for universal movement so as to be movable transversely of the rack into and out of engagement therewith, and also so as to have letter-spacing movement in the direction of the length of the rack, key-operated means 95 for operating the pawl including an operating link connected to the pawl in such manner that its leverage in relation to the pawl as the pawl moves transversely of the rack will be at least as great as the leverage 100 exerted thereby on the pawl for moving it in the direction of the length of the rack, and a restoring spring for the pawl acting through the link for normally holding the pawl out of engagement with the rack and 105 at a retracted letter-spacing position.

6. In a typewriting machine, the combination with a traveling carriage and an escapement mechanism therefor, including a rack connected to the carriage to travel 115 therewith, of back-spacing mechanism comprising a back-spacing pawl pivoted for movement transversely of the rack into and out of engagement therewith, and also so as to have letter-spacing movement in the direction of the length of the rack, key-operated means for operating the pawl including an operating link connected to the pawl in such manner that its leverage in relation to the pawl as the pawl moves transversely 120 of the rack will be at least as great as the leverage exerted thereby on the pawl for moving it in the direction of the length of the rack, a restoring spring for the pawl acting through the link for normally hold- 125 130

ing the pawl out of engagement with the rack and at a retracted letter-spacing position, and a spring normally overcome by the pawl-restoring spring but continually urging the pawl toward the engaging position for moving it into engagement with the rack when the pawl-restoring spring is overcome by the operation of the key.

7. In a typewriting machine, the combination with a traveling carriage having an escapement rack connected to the carriage to travel therewith, of back-spacing mechanism comprising a back-spacing pawl pivoted for movement transversely of the rack into and out of engagement therewith, and also for letter-spacing movement in the direction of the length of the rack, a key-operated lever arm for operating the pawl, an operating

link connecting the lever arm with the pawl, a pawl-restoring spring acting through the link for normally holding the pawl out of engagement with the rack and at a retracted letter-spacing position, and a spring normally overcome by the pawl-restoring spring but continually urging the pawl toward the engaging position for moving it transversely of the rack into engagement with the rack when the pawl-restoring spring is overcome by the operation of the key, the key then acting through the lever arm and link to impart letter-spacing movement to the pawl to move the rack for back-spacing the carriage.
